CHRISTMAS TREE

Vincent J. Aquilante, Providence, R.I., assignor of fractional part interest to George E. Reilly, Woonsocket, R.I.

Filed Jan. 28, 1974, Ser. No. 437,485

Term of patent 7 years

Int. Cl. D11—02

U.S. Cl. D29—1 A

FIG. 1

FIG. 2

FIG. 3

FIG. 1 is a side elevational view of a Christmas tree showing my new design;

FIG. 2 is a bottom plan view thereof; and

FIG. 3 is a top plan view thereof.

I claim:

The ornamental design for a Christmas tree, substantially as shown.
